UNITED STATES PATENT OFFICE.

THEODORE R. VINZENT, OF SALEM, OREGON, ASSIGNOR OF ONE-THIRD TO
JOSEPH GRAF, OF SAME PLACE.

PERMUTATION-PADLOCK.

SPECIFICATION forming part of Letters Patent No. 585,013, dated June 22, 1897.

Application filed October 16, 1896. Serial No. 609,099. (No model.)

To all whom it may concern:

Be it known that I, THEODORE R. VINZENT, of Salem, in the county of Marion and State of Oregon, have invented a new and Improved 5 Permutation-Padlock, of which the following is a full, clear, and exact description.

The object of the invention is to provide a new and improved permutation-padlock which is simple and durable in construction, 10 cheap to manufacture, and arranged to enable the owner to readily change the combination to prevent unauthorized persons from tampering with the lock.

The invention consists of certain parts and 15 details and combinations of the same, as will be fully described hereinafter and then pointed out in the claims.

Reference is to be had to the accompanying drawings, forming a part of this specification, 20 in which similar characters of reference indicate corresponding parts in all the figures.

Figure 1 is a perspective view of the improvement. Fig. 2 is a sectional side elevation of the same. Fig. 3 is a face view of one 25 of the tumblers. Fig. 4 is a cross-section of the improvement on the line 4 4 of Fig. 2. Fig. 5 is a side elevation of the several tumblers, and Fig. 6 is a broken perspective view of the bolt.

30 The improved padlock is provided with two heads A and B, provided with bars A' B', respectively, of which the bar B' has a reduced end B², adapted to engage a correspondingly-shaped socket A², formed in the end of the other bar A'. From the head A extends parallel to the arm A' a sleeve C, the free end of which abuts on the head B and the said sleeve is adapted to be engaged by a bolt D, projecting from this end of the head B.

35 The bolt D is provided with a number of lugs D' D² D³, placed suitable distances apart and adapted to pass through a longitudinal slot C', formed in the sleeve C, and into transverse recesses C² C³ C⁴, respectively formed 40 in the said sleeve, as indicated in Fig. 2. When the lugs D' D² D³ register with the said recesses C² C³ C⁴, then the bolt D is partly withdrawn from the sleeve C and the reduced end B² of the bar B' is then out of the socket

A² to permit of turning the head B, so as to 50 open the bars A' and B'.

On the sleeve C are mounted to turn the tumblers E, F, and G, separated from each other by collars C⁵, secured on the said sleeve. The tumbler E is formed in its periphery 55 with longitudinal slots E', one of which is adapted to be engaged by a key H', formed on a shell H, mounted to turn at one end on an offset A³, formed on the head A, and at its other end on a collar I, screwing on the sleeve 60 C, the said collar being formed with recesses I', adapted to be engaged by pins B³, projecting from the head B for locking the latter against turning. The key H' is adapted to engage, with the end projecting beyond the inner face of the tumbler E, the end F' of a bar 65 F², held in one of the recesses F³, formed on the periphery of the tumbler F. The bar F² is adapted to be inserted in any one of the recesses F³, according to the desired combination, and the bar is held in place in the corresponding recesses by a spring F⁴, in the shape of an open ring, fitted into an annular 70 groove F⁵, formed at or near the middle of the tumbler F. The bar F² has its other end 75 F⁶ projecting beyond the other face of the tumbler F, as shown in Fig. 5, and this end F⁶ is adapted to engage the end G' of a bar G², held in one of a series of longitudinal recesses G³, formed in the third tumbler G. A 80 spring G⁴ serves to hold the bar G² in place in the corresponding recess G³.

Each of the tumblers E F G is formed at its bore with a recess E² for the passage of the lugs D' D² D³ of the bolt D, so that the bolt 85 D cannot be withdrawn from the sleeve C unless the recesses E² in the several tumblers register with the longitudinal slot C' of the sleeve C. The face of each of the tumblers is marked or graduated, preferably as indicated in Figs. 3 and 4, a numeral being for each slot, so as to indicate the location of the corresponding bar F² or G² relatively to the tumblers F and G and the key H' relatively to the tumbler E.

90 It is evident that by the arrangement described the operator can set the key H' to engage the desired numbered recess E' in the

tumbler E, so that the turning of the shell II causes the key II' to turn the tumbler until its recess E² is in alignment with the slot C'. As the key II' is also in the path of the end F⁶ of the bar F², it finally moves into engagement with the said end to turn the tumbler F until the latter is brought in position with its notch registering with the slot C'. As the other end F⁶ of the bar F² is adapted to engage the end G⁶ of the bar G², the tumbler G is turned until its notch comes in register with the slot C'. Of course the tumblers can only be turned into these positions if a person knows the combination at which the padlock is set, and when the several tumblers are in this position the head B can be moved outward, so as to disengage the reduced end B² from the socket A² and permit of turning the head B, with the bolt D as the spindle, so as to completely open up the bars A' and B'. The outward sliding motion of the head B with the bolt D is limited by the first lug D' abutting against the inner face of the collar I. It will be seen that by the arrangement described the owner of the padlock can readily change the combination whenever desired, so as to prevent unauthorized persons from tampering with the lock. The shell II is formed at one outer end with a graduation II², reading off on a mark formed on the head A, so as to enable the operator to readily turn the shell II to bring the several tumblers into the proper position for opening the lock, as above described.

Having thus fully described my invention, I claim as new and desire to secure by Letters Patent—

1. A permutation-padlock, provided with a sleeve having a longitudinal slot, transverse recesses leading from the said slot, tumblers mounted to turn on the said sleeve and formed with recesses adapted to register with the slot in the said sleeve, a bolt adapted to engage the said sleeve and having a series of lugs engaging the said slot, and recesses in the said sleeve and in the said tumblers, substantially as shown and described.

2. A permutation-padlock, provided with a sleeve having a longitudinal slot, transverse recesses leading from the said slot, tumblers mounted to turn on the said sleeve and formed with recesses adapted to register with the slot in the said sleeve, a bolt adapted to engage the said sleeve and having a series of lugs engaging the said slot, recesses in the said sleeve and in the said tumblers, and a shell mounted to turn and formed with an internal key adapted to engage recesses in one of the tumblers and the projecting end of a bar in another tumbler, substantially as shown and described.

3. A permutation-padlock, provided with a sleeve having a longitudinal slot, transverse recesses leading from the said slot, tumblers mounted to turn on the said sleeve and formed with recesses adapted to register with the

slot in the said sleeve, a bolt adapted to engage the said sleeve and having a series of lugs engaging the said slot, recesses in the said sleeve and in the said tumblers, a shell mounted to turn and formed with an internal key adapted to engage recesses in one of the tumblers and the projecting end of a bar in another tumbler, and a bar in the third tumbler and adapted to be engaged by the projecting end of the bar in the second tumbler, substantially as shown and described.

4. A tumbler for permutation-locks the tumbler having a curved side with a recess running across said curved side, a bar located within said recess, and a curved spring embracing the curved portion of the tumbler and engaging the bar to hold it in position, substantially as described.

5. A circular tumbler for permutation-locks the tumbler having a groove running across one side thereof and also having a groove running around it, a bar held in the first-named groove, and a curved spring lying in the second-named groove and embracing the bar to hold it in position, substantially as described.

6. The combination of a bolt having a projection, a sleeve loosely receiving the bolt and having a longitudinal slot with an offset portion receiving the projection, a tumbler turning on the sleeve and having a recess in its bore capable of registering with the projection of the bolt, and a shell inclosing the parts of the lock and turning around the tumbler and capable of adjusting the same, substantially as described.

7. The combination of a bolt, a sleeve loose on the bolt and having a slot with an offset receiving the projection of the bolt, a tumbler turning around the sleeve and having an interior groove capable of registering with the projection, the tumbler also having a groove in its outer side, and a shell inclosing the parts of the lock and having a key fitting within the groove in the outer side of the tumbler, substantially as described.

8. A permutation-lock having two heads, each head having a bar, the outer ends of which are capable of engaging with each other, a bolt secured to one head and having a plurality of longitudinally-aligned projections, a sleeve secured to the second head and loosely receiving the bolt, the sleeve having a longitudinal slot with offset portions respectively receiving the projections of the bolt, a plurality of tumblers turning on the sleeve, each tumbler having a groove running through its bore, and the groove being capable of alignment with the projection on the bolt, a shell turning around the tumblers and transmitting movement to one tumbler whereby that tumbler is adjusted, and means for transmitting movement from the said tumbler to the remaining tumblers, substantially as described.

9. The combination of a bolt having a pro-

jection, a sleeve loose on the bolt and having a longitudinal slot receiving the projection, a tumbler turning on the sleeve and having a recess in its bore capable of registering with the projection on the bolt, and a shell surrounding the tumbler and capable of movement to adjust the same with reference to the

projection on the bolt, substantially as described.
